UNITED STATES PATENT OFFICE.

GEORGE W. ALTMAN AND PETER K. MEECH, OF HUNTINGTON, INDIANA.

BROOM-HOLDING RACK.

SPECIFICATION forming part of Letters Patent No. 357,057, dated February 1, 1887.

Application filed August 9, 1886. Serial No. 210,461. (No model.)

To all whom it may concern:

Be it known that we, GEORGE W. ALTMAN and PETER K. MEECH, citizens of the United States of America, residing in Huntington, 5 county of Huntington, and State of Indiana, have invented a new and useful Broom-Rack, of which the following is a specification.

Our invention relates to improvements in broom-racks; and it consists in the novel features more fully hereinafter described, and shown in the annexed drawing, in which is shown a perspective view of the rack in use, in which—

B is a loop on which is placed bars *a*, provided at each end with broom-securing clips A substantially in the form of an ellipse having an opening in one side for the reception of the broom. The broom-receiving clips may be integral with the rods *a* or be separate, as 20 desired. The hoop and bars are fastened securely to each other at their point of intersection, and still greater stability is given the device by fastening the bars *a* together at their point of intersection in the center *d*.

25 Cords or wires *c* are attached to different points on the hoop B, and are connected together at a point directly over the center, and are joined to the cord or wire D, suspended from the ceiling. The cord D is connected to 30 the rack at the center *d*, and the other end is secured to the floor or other suitable place, to prevent the rack swinging.

Having thus described our invention, what we claim, and desire to secure by Letters Patent, is—

1. The herein-described broom-rack, composed of bars arranged radially to each other, and having at the ends broom-receiving clips substantially in the shape of an ellipse, and having an opening in one side for the passage 40 of the handle of the broom, and means, substantially as specified, for supporting said bars, substantially as set forth.

2. The herein-described broom-rack, composed of bars arranged radially to each other 45 and crossing at or near their middle, and having broom-receiving clips at each end of and projecting horizontally in opposite directions from the sides of the bars, and means, substantially as specified, for supporting said bars, 50 substantially as shown, and for the purpose described.

3. The herein shown and described broom-rack, composed of bars crossing each other near their middle, each bar having at its opposite ends and integral therewith broom-receiving clips substantially in the shape of an ellipse, and having an opening formed in one side thereof, which clips extend in opposite directions from the sides of the bars, the hoop 60 secured to the bars near their ends for supporting said ends, and the supporting-cords, substantially as set forth.

GEORGE W. ALTMAN.
PETER K. MEECH.
